DESIGN FOR A DRAIN BOARD

Julian L. Perkins, West Springfield, Mass.

Application September 18, 1936, Serial No. 64,913

Term of patent 3½ years

To all whom it may concern:

Be it known that I, Julian L. Perkins, a citizen of the United States, residing at West Springfield, in the county of Hampden and State of Massachusetts, have invented a new, original, and ornamental Design for a Drain Board, of which the following is a specification, reference being had to the accompanying drawing, forming part hereof:

Fig. 1 is a plan view of a drain board embodying my design;

Fig. 2 is an end elevational view of the same; and

Fig. 3 is a perspective view of the drain board shown in Figs. 1 and 2.

I claim:

The ornamental design for a Drain Board as shown.

JULIAN L. PERKINS.
